FEEDING CUP FOR MINKS OR THE LIKE

Harold Rossing and Dann L. Rossing, Fort Atkinson, Wis.

Application April 10, 1957, Serial No. 45,678

Term of patent 14 years

(Cl. D12—2)

Fig. 2 is a sectional view taken on line 2—2 of Fig. 1.

Fig. 3 is a sectional view taken on line 3—3 of Fig. 1.

Fig. 4 is a top plan view of the feeding cup.

We claim:

The ornamental design for a feeding cup for minks or the like, as shown.
